UNITED STATES PATENT OFFICE

JAMES TILLOTSON, JR., OF JAMESTOWN, NEW YORK, ASSIGNOR TO THE JAMESTOWN RADIO CABINET CORPORATION, OF JAMESTOWN, NEW YORK, A CORPORATION OF NEW YORK

DESIGN FOR A RADIOTABLE

Application filed October 8, 1929. Serial No. 32,978. Term of patent 3½ years.

To all whom it may concern:

Be it known that I, JAMES TILLOTSON, JR., a citizen of the United States, residing at Jamestown, in the county of Chautauqua and State of New York, have invented a new, original, and ornamental Design for a Radiotable, of which the following is a specification, reference being had to the accompany-

ing drawing, forming part thereof, and in which the figure is a view showing in perspective the front and side of the newly designed radiotable.

I claim:

The ornamental design for a radiotable substantially as shown.
